UNITED STATES PATENT OFFICE

107,231

DESIGN FOR A PLAQUE

Samuel L. Hefter, Chicago, Ill.

Application September 7, 1937, Serial No. 71,489

Term of patent 3½ years

To all whom it may concern:

Be it known that I, Samuel L. Hefter, a citizen of the United States, residing at Chicago, in the county of Cook and State of Illinois, have invented a new, original, and ornamental Design for a Plaque, of which the following is a specification, reference being had to the accompanying drawing, forming part thereof.

Figs. 2, 3, 4, and 5 are sectional views taken on the lines 2—2, 3—3, 4—4 and 5—5 of Fig. 1, respectively.

I claim:

The ornamental design for a plaque as shown.

SAMUEL L. HEFTER.
